UNITED STATES PATENT OFFICE.

FRANCIS FALCONER DAVIS, OF MOUNT VERNON, OHIO, ASSIGNEE TO FRANCIS HARLEY
DAVIS, OF MONTEREY, CALIFORNIA.

DRILLING APPARATUS.

Application filed June 12, 1923. Serial No. 644,912.

This invention relates broadly to apparatus for drilling holes in the earth's strata or other purposes known to the art. It is adapted for core-drilling but may be used to 5 cut away the entire content of a borehole by the substitution of a different bit.

Specifically it is an improvement on the type known as Davis calyx drills for which reissue Letters Patent of the United States, 10 No. 11,597 were granted to Francis H. Davis, April 27th, 1897, in which, embodied as separate items are two salient features consisting of; first, a drilling or boring element which while in operation produces chips or 15 grindings; second, a chip-cup, sludge-barrel or calyx element which collects such matter as is produced by the drilling element.

Drills of this type are of a many-jointed construction having been originally designed 20 to operate under the slow rate of rotation necessary when drilling with a Davis cutter,—say from four to six turns per minute and largely on that account fail in many ways to meet present conditions, wherein 25 most of the drilling is done by some form of abrasive cutting medium such as chilled iron shot, or crushed steel, the use of which requires a rapidly rotated drill—three or four hundred revolutions per minute.

Under the former conditions a jointed construction comprised in such an apparatus 30 may have been admissible; but where, as is the case in shot drilling, whole shot and shot particles unite with borehole sludge and 35 form a grinding paste of such destructive ability as the closest joints and hardest steel fail to withstand; the fewer joints the better.

As my improvement has largely to do with the elimination of certain unnecessary and 40 objectionable joints in a drilling apparatus of this kind I will discuss them in relation to the former art and in contrast with my improved and novel construction:—

Referring to Reissue, No. 11,597 above 45 mentioned, Sheet 1 Figure 4 it is apparent that the first weak spot in the construction, counting from the drill up, is where the rod connects with the corebarrel-plug C. This 50 joint is the most fruitful cause of trouble in apparatus of this kind. The majority of the many drills which break off down boreholes break short off at the joint A—C. This is caused in part by the inflexuous rigidity of the apparatus at C and the flexibility 55 of the rod A, which of much smaller

diameter than the borehole and having no rigid support from a shot-worn joint at B—C to enable B to keep A in true axial alignment is free to lash and vibrate violently in the borehole under torsional strain 60 and end pressure while drilling. The tendency to break at this point is augmented further by shocks imparted to A by a heavily-loaded, loose-jointed calyx when whirled round with rapidity and force, this undoubtedly tends to crystalize the rod and cause shot particles to work into the joint; which, be it observed, is right in the very bottom of the calyx where the steel particles are naturally most abundant. My improvement as 70 will be seen eliminates this joint.

When under such conditions as outlined above a rod A breaks at A—C the calyx B generally comes to the surface with the withdrawal of the drill rod A. When B is lifted 75 from its seat on C it spills its entire contents on and around the drill producing a serious situation that in many cases has been overcome by drilling through the core-barrel-plug C with a smaller sized drill so as to go 80 on down through the drill and continue the borehole with a smaller size; although it not infrequently occurs that owing to the flogging action of one drill within the other the stuck drill becomes loosened and may be 85 fished out in which case the borehole may be continued without reduction at this point.

Such a fishing operation to be successful 90 depends critically upon the ability to center the smaller drill in true axial alignment with that of the stuck drill and not come down on it foul. The chances are against success, and in any case some of these core barrel-plugs C are formidable chunks of metal, for 95 boreholes of several feet in diameter such as have been drilled abroad require them to be large; even when cut through by such smaller drill the resulting core that falls down into the corebarrel ahead of the smaller drill often gives serious trouble. My improvement does away with these costly and 100 objectionable corebarrel-plugs and substitutes a wooden plug therefor.

This is not a hypothetical case but one 105 that has occurred to me several times and to others. Sometimes the problem works out successfully at other times the hole has to be abandoned, often at great monetary loss.

Having in this preamble described some 110 of the limitations inherent to apparatuses

of the kind mentioned and their inability to meet the present conditions I will now state the objects of my improvements:—

One object is to provide a drilling apparatus in which corebarrel and calyx are substantially composed of one integral piece or that are otherwise provided with joints judiciously located at points where flexure is reduced to a minimum and shot particles are not liable to do them injury.

Another object is to provide a diminishing tapering neck to the apparatus that will act to absorb shocks where drilling apparatus and drillrod meet, and that may serve as a center to guide one drill over another in case it has to be drilled into.

Another object is to provide a thin shell where one drill would drill into the other.

Another object is to furnish the upper portion of such an apparatus with one or more openings whereby drillhole-matter may by following the line of least resistance find access to the interior of the calyx element.

A further object is to provide a novel connecting coupling, adapted to couple the tapered end of the apparatus to a drillrod in such wise that it may receive movement therefrom, said coupling also adapted to act as the means of suspending with fluid-tight connection, a wash-pipe or duct connecting with a bulkhead located in the interior of the apparatus.

A still further object is to provide a drilling apparatus of such construction that the burden of the detritus ascending the bore-hole shall find its way into the calyx before coming in contact with any flexuous joint.

A further object is to provide a structure of apparatus better adapted for drilling a true hole, by reason of its rigidity and because the point of connection between apparatus and drillrod is farther up from the bottom.

An additional object of shifting the drive from the corebarrel-plug C of the older patent to the top of the calyx element as comprised in my improvement is that when drillrods do break off at the latter point they may be withdrawn without dumping the contents of the calyx on top of the drill.

The fact should be fully realized that there is no known substance proof against the continuous attack of these shotty particles, they will through chilled iron castings, steel beams, anvils, the hardest rock and even the diamond could be drilled by their agency; it is imperative to exclude such particles from all joints, particularly so from those subject to shock and the peculiar creeping action of a drillrod set up by the varying resistance of a revolving drill.

An important object is to provide an apparatus in which the calyx element transmits motion to the drilling element instead of the drill element transmitting motion to the

calyx element, as is the case in former constructions.

Another object is to provide a soft bulk-headplug, preferably of wood, to separate the calyx element from the drilling element.

Another object is to provide a washpipe or duct to act as conduit means to convey water or fluid through the calyx member and form part of the wall thereof.

The combined objects tend to make a drill of novel construction and of greater efficiency, one less liable to breakage, more easily fished out when broken, one that costs less to make and that will give longer service with fewer repairs than drills of former type.

Further objects and novel features will be fully described in connection with the accompanying drawings and will be more particularly pointed out in and by the appended claims.

In the drawings:—

Figure 1 shows my drilling apparatus in vertical elevation complete as it would appear at work drilling in the earth's strata, the latter being shown in section.

Fig. 2 shows in vertical middle section the same parts of the apparatus as shown in Fig. 1.

Fig. 3 shows a cross section on line 3—3 of Fig. 1.

Fig. 4, sectional elevation of upper portion of apparatus.

Fig. 5 shows another form of Fig. 4 illustrating tube 5 acting as re-enforcement to neck of apparatus.

Like characters of reference refer to like parts throughout the different figures of the drawing,—in this instance numerals; whereas, the parts in United States Re-issue Patent No. 11,597, to which frequent references are made, are designated by capital letters.

Referring more fully to the inability of drills of this former type to make good at shot-drilling, will say that during twenty years experience as a drill operator, mostly with drills of this kind I have never seen or heard of any form of calyx holder that will hold. In spite of all efforts in this direction, and much attention has been turned toward it, there is no device extant that will hold a calyx down on corebarrel-plug C and concentric with drill-rod A. In consequence of this, calyx B soon works loose and fails to keep up with the drill as it revolves. This sets up such a grinding action at the seat B—C that the joint will not retain the calyx matter but allows it to circulate in and out of tube B, now no longer a calyx but a loose tube riding round by jerks on C to the ruin of both.

The function of the calyx is to collect drillings and the like. Normally there is a balance between the footage drilled and the quantity of matter for the calyx to care for. A calyx that will not retain its contents, or

that has inadequate capacity to contain the amount of calyx matter resulting from a given footage drilled, hampers the operation of an abrasive drill by requiring an excessive fluid current to keep a mass of cuttings in suspension which should, by rights, have been taken care of by the calyx as produced, such excessive current tends to carry the abrasive from under the drill and reduce its efficacy.

In my novel and improved drilling apparatus there are no such joints as those comprised by the juncture of A—C and C—B or of the rod A and the pins J of Reissue Patent No. 11,597, before-mentioned.

My bulkhead 6 when subjected to water action swells so tight inside the apparatus that it becomes practically immovable, then again, it is not subjected to movement, endwise or torsional. Calyx matter having once entered my improved calyx through the perforations provided for such purpose stays there until it is desirable to have it removed; moreover, tube 5 having nothing whatever to do with driving the drill may be relatively smaller in diameter than drill-rod A which in the reissue aforesaid performs that function, being smaller it leaves more room for cuttings in the calyx.

My improved drilling apparatus consists of a tubular structure 1 provided with a drill member 2 either as a separate member or formed by the slot-and-heel feature 12 being cut on the end of the corebarrel 8, direct.

The upper portion of the apparatus 1 is provided in some instances with a diminishing neck 10, tapering smaller toward the upper end which is furnished with means of attachment to drill-rod 4 by coupling 3 or other suitable means; said upper portion of the drilling apparatus being provided with one or more perforations as 7.

Interiorally the apparatus 1 is provided with tube 5 extending a predetermined distance upward from the bulkhead-plug 6. When secured in place as shown in the drawings, 5 and 6 serve to separate the interior of drilling apparatus 1 into the two compartments, comprising, the drill element 8 and the calyx element 9 and also provide for fluid passageway therethrough from the drill-rod 4.

In Fig. 5 is shown another form of upper end for the apparatus more adaptable for drills of smaller size the parts 1^a, 3^a, and 10^a of which are similar to the parts 1, 3 and 10 of Figs. 1-4.

While I have shown the apparatus 1 as a core drill, yet it is obvious that my improvement applies equally well to any combination of calyx and drill wherein cuttings are removed from the drill and stored in the calyx by fluid means.

Tube 5 rigidly attached to bulkhead 6

may be slipped into the apparatus 1 from the lower end until the thread on 5 engages with a counterpart at upper end of apparatus where they may be securely screwed together by an extension wrench, or by other suitable means applied to boss 11, the said boss 11 may be integral with tube 5 as shown or otherwise rigidly attached thereto.

When in operation the drilling apparatus 1 gets its movement from the drill-rod 4, 75 being coupled thereto, 4 being energized by some form of drilling mechanism. The apparatus is provided with a drilling means and a fluid agency under regulated pressure which passes down through drill-rod 4 and tube 5, thence to the bit 2 where it passes through slot 12 turns and comes up the bore-hole lifting cuttings, débris and the like with its upward flow, carrying them up between the outer structure of the drilling apparatus and the wall of the borehole to the point where the perforations 7 are met; here, following the line of least resistance, they pass through said perforations and subside into the calyx element of the apparatus 90 1, to be drawn up with the withdrawal of the drilling apparatus, from which they can be removed by the insertion of a hose or suitable means adapted for flushing out the calyx reservoir so that it may be empty on 95 its return to the borehole.

While I have herein shown and described specific forms of my invention I do not wish to be limited thereto except by such limitations as the claims may import.

I claim:

1. In a calyx drill apparatus of the kind described, an elongated tubular structure comprising a drill element and a calyx element means for carrying fluid through the 105 calyx and a bulkhead adapted to close the bottom end of the calyx, the said bulkhead composed of substance that will swell when wet, as wood.

2. A calyx drill apparatus of the kind 110 described, comprising in combination, an elongated tubular structure comprising a drill element and a calyx element, means for carrying fluid through the calyx and a bulkhead adapted to close the bottom end of the 115 calyx, the said bulkhead composed of substance that will swell when wet, as wood.

3. In a calyx drill of the kind described having an elongated tubular structure, a calyx element, a tubular drill-barrel element, means for carrying fluid through the calyx, an internal bulkhead adapted to close the bottom end of the calyx, the said bulkhead being further adapted to be inserted, assembled, and removed with relation to the structure without any dismemberment of the 120 said elongated tubular structure.

4. A calyx drill of the kind described, comprising in combination, an elongated 125 tubular structure partitioned internally by a

- bulkhead so as to form a calyx above the bulkhead and a drill-barrel element below the bulkhead, said bulkhead forming a closure for the bottom of the calyx, a duct 5 means for carrying fluid through the calyx, the said bulkhead being further adapted to be inserted, assembled, or removed with relation to the elongated tubular structure without there being any dismemberment of the 10 said elongated tubular structure per se.
5. In a calyx-driven apparatus of the kind described; an elongated tubular structure; means for carrying fluid through the calyx; an internal self-expansive bulk-head; upper 15 portion of tubular structure conformed to exclude said bulk-head; lower portion of tubular structure and body of tubular structure adapted to receive said bulk-head; the said bulk-head being adapted to be pressed 20 up into the said tubular structure from the lower end of said structure and further adapted to be secured therein, or to be removed therefrom by means operating thru said lower end of said structure.
- 25 6. In a calyx-driven apparatus of the kind described and in combination; an elongated tubular structure; a means for carrying water through the calyx; an internal self-expansive bulk-head means adapted to close 30 the bottom of the calyx; upper portion of the tubular structure conformed to exclude entrance of the said bulk-head thereto; lower portion of the tubular structure adapted 35 to receive the bulk-head; said bulk-head being adapted to be pressed away up into said tubular structure from the lower end thereof, adapted also to be secured in said structure or to be removed therefrom by means operating thru said lower end of the 40 apparatus.
7. A calyx drilling apparatus comprising in combination, a drill member, a calyx structure adapted to drive drill, means for connecting said calyx to a drill-rod, duct- 45 means for carrying fluid from drill-rod through the calyx structure, suitable perforations in calyx structure, a bulkhead partitioning calyx compartment from drill member, said bulkhead rigidly secured to the lower end of said duct, and counterpart 50 means adapted to be secured by an independent agent for assembling the said duct and bulkhead within the apparatus.
8. In an apparatus of the kind described

having a tubular structure, a calyx element, 55 a tubular drill-barrel element, means for carrying fluid through the calyx, an interior bulkhead adapted to close the bottom of the calyx, the said bulkhead composed of substance that will swell when wet and being 60 located within a jointless portion of the said structure, substantially as, and for the purpose set forth.

9. An apparatus of the kind described having a tubular structure, comprising in 65 combination, a calyx element, a tubular drill-barrel element, means for carrying fluid through the calyx, an interior bulk-head adapted to close the bottom of the calyx, the said bulkhead composed of substance that will swell when wet and being 70 located within a jointless portion of the said structure, substantially as described.

10. An apparatus of the kind described having a jointless tubular structure, a calyx 75 element, a drill-barrel element, a drill member, means for carrying fluid through the calyx, a bulkhead that will swell when wet and close the bottom of the calyx.

11. An apparatus of the kind described 80 having a jointless tubular structure comprising in combination, a calyx element, a drill-barrel element, a drill member, means for carrying fluid through the calyx, a bulk-head that will swell when wet and close the 85 bottom of the calyx.

12. In an apparatus of the kind described having an elongated tubular structure with a tapered neck whose wall is relatively thicker than the wall of the structure, a bulkhead partitioning the structure into a drill-barrel element and a calyx element, a pipe for carrying fluid through the calyx, the upper end of the pipe being adapted to reinforce the said neck and to fasten thereto. 95

13. An apparatus of the kind described having an elongated tubular structure comprising in combination, a tapered neck whose wall is relatively thicker than the wall of the structure, a bulkhead partitioning the 100 structure into a drill-barrel element and a calyx element, a pipe for carrying fluid through the calyx, the upper end of the pipe being adapted to reinforce the said neck and to fasten thereto. 105

In testimony whereof I affix my signature.

FRANCIS FALCONER DAVIS.
